Filed Aug. 15, 1960, Ser. No. 49,599
8 Claims. (Cl. 34—122)

This invention relates to paper web dryers, and more particularly to a hot air dryer for use in conjunction with a dryer shell to remove moisture from a moving web of paper.

The dryer of this invention is constructed of a plurality of separate modules or units arranged and mounted in contiguous relation one to the other to form a completed dryer. The dryer is mounted transversely to a moving web of paper to direct heated air in impinging relation against the surface of such a web moving over a dryer shell. The combined dryer units are supported on a lifting frame for initial alignment with the shell and for two-way adjustable radial movement relative to the shell. The arrangement of the lifting frame provides a dryer having uniform and constant clearances between the dryer units and the shell.

The individual units which make up the complete dryer each include an arcuate nozzle assembly incorporating nozzles for directing heated gases into impingement with the paper, and return openings for the withdrawal of moist air from the region between the nozzle assembly and the web. The nozzle assembly is connected to a supply duct portion of the unit preferably through a variable damper, and the return openings are similarly connected to a return duct through a variable damper. The dampers are adjustable to regulate the rate of hot air application to the web thereby providing control of the drying effect of each individual unit at arcuate segments of the shell. Each of the adjacent units is preferably similarly provided with dampers to provide for profile control of the moisture content of the moving web.

The position of the air dampers may be manually or remotely controlled, and remote control is conveniently effected through a separate air piston and bell crank assembly for each unit, for the simultaneous movement of a pair of damper plates. The supply and return duct portions of the individual units open into similar portions of adjacent units to form common supply and return passageways which are connected at the inner end of the dryer to the usual heated air supply and return ducting.

The lifting frame for moving the assembled dryer units radially toward and away from the shell includes a pair of spaced apart support rails mounted at opposite ends on screw jacks. The jacks are mechanically interconnected to each other and provide for leveling adjustment of the four corners of the dryer as well as for uniform raising and lowering movement by reason of the mechanical interconnections.

The individual units are supported on the rails and are held in contiguous relation by tie bolts providing for expansion with heat in the longitudinal direction with the rails. The width of the individual units is such as to provide effective control of the drying of a web adjacent a segment of the shell in order to compensate for the effect of air escape at the edge, and to provide uniform drying of the web. The dryer of this invention is characterized by high air capacity and efficiency, and is adapted

2

for operation with varying paper widths by the addition of units or by the closure of the dampers of existing units.

It is therefore a principal object of this invention to provide a dryer as outlined above characterized by versatility and high drying capacity.

A further object of this invention is to provide a dryer as outlined above being made up of an assembly of individual units forming common supply and return chambers and each having separately controllable nozzle assemblies.

10 Another object of this invention is to provide a dryer as outlined above having a plurality of dryer nozzle assemblies each of which are individually controllable to profile the drying of a paper web.

A particular object of this invention is to provide such a dryer including a mounting frame and mechanism for moving the dryer radially toward and away from a shell.

15 A still further object of this invention is to provide a dryer having a mechanically interconnected lifting arrangement for the individual leveling and uniform movement of the four corners thereof to establish and maintain a minimum running clearance.

20 Other objects and advantages of the invention will be apparent from the following description, the accompanying drawings and the appended claims.

25 In the drawings—

FIG. 1 is a partially broken away perspective view of a dryer constructed in accordance with this invention;

FIG. 2 is a plan view of the lifting and support frame arrangement of the dryer;

FIG. 3 is an end view of the frame of FIG. 2;

FIG. 4 is an elevational view of one of the individual drying units;

FIG. 5 is a section through the unit of FIG. 4 taken generally along the line 5—5 of FIG. 4;

FIG. 6 is a section through the unit of FIG. 4 showing the arrangement of the air dampers taken generally along the line 6—6 of FIG. 4;

FIG. 7 is a section through one of the dampers taken along the line 7—7 of FIG. 4;

FIG. 8 is an enlarged fragment, partially in section, showing the arrangement of one of the nozzle assemblies;

FIGS. 9a and 9b are sections through the nozzle assembly of FIG. 8 taken respectively along the lines 9a—9a and 9b—9b; and

FIG. 10 is a partial section taken generally along the line 10—10 of FIG. 2 showing the arrangement of the position limit switch.

50 Referring to the drawings, which illustrate a preferred embodiment of the invention, a dryer constructed in accordance with this invention is illustrated in FIG. 1 as including a front support stand 11 and a rear support stand 12. The support stands 11 and 12 each include upright legs 13 and 14 connected by a transverse support bar 15. A pair of spaced apart channel-section support rails 17 and 18 extend between the support bars 15 of the stands 11 and 12 and have their opposite ends supported for vertical movement on screw jacks 20. Horizontal lifting plates 21 are welded in extending relation adjacent each end of the rails 17 and 18 for engagement with the operating head of the jacks 20.

55 The jacks 20 are mechanically interconnected to each other for simultaneous movement by means of a pair of end shafts 22 and 23, as is best shown in FIGS. 2 and 3. The end shafts 22 and 23 and the associated jacks 20 are operated through 90° miter drives 24 and 25 interconnected by a shaft 26 extending longitudinally of the dryer. A reversible electric motor 30 is connected to drive an input shaft 31 connected to the drive box 25 to effect the simultaneous raising and lowering of the side rails 17 and 18 by the four screw jacks 20. FIG. 3 shows

3
the dryer in typical operative relation with a dryer shell 33, and the position of any one of the jacks 20 may be adjusted by disconnecting the adjacent coupling 34 and turning the jack to the desired position, to effect the leveling of the dryer in relation to the dryer shell 33.

It will be understood that the arrangement of the support stands 11 and 12 and their relation to the rails 17 and 18 may be varied without departing from the scope of this invention. For instance, the dryer may be used in conjunction with the bottom portion of a dryer shell rather than the top as illustrated in FIG. 3, and in this case the support stands would support the dryer sections in inverted relation.

The body of the dryer consists of a plurality of separate dryer units 40 which are mounted in contiguous relation to each other on the support rails 17 and 18 transversely of the associated dryer shell, and each of the units 40 is notched or recessed at 41 on each side to receive the support rails 17 and 18. The units 40 preferably occupy a relatively small portion of the total width of a web on such shell, but the total width of the combined units is at least as wide, and preferably wider than the web to be dried thereby.

The assembled dryer is provided with an outside end unit 45 which differs from the remainder of the units 40 only in the provision of an end closure plate 46 and a pair of inspection doors 47 and 48 which close the end of the supply and return ducts. The inside end unit 40 is arranged to connect with external hot air supply and return ducts 49 and 50 through a quick disconnect coupling 52.

The units 40 are formed of welded sheet metal and consist of an upper portion 60 and a lower portion 61 which are positioned approximately equally above and below the rail-receiving recess 41 formed in the units. The upper portion 60 includes sheet metal side walls 62 and 63 which have inspection openings 64 formed therein, a bottom partition 65 separating the upper and lower portions of the unit 40, and a top 66. The units 40 preferably include insulated sides and tops for the retention of heat energy within the dryer. Thus, the top 66 is insulated by fiberglass batting held in place by a finishing cover 67. Side covers 68 conceal the inspection openings 64 and also contain insulation.

The side walls 62 and 63 and the top 66 of each unit 40 are flanged at 69 to receive a high temperature separating gasket between adjacent units. A flanged divider 70 separates the upper portion 60 into an open supply duct portion 74 and an open return duct portion 75 which are combined with similar portions of adjacent units to provide common inlet and return passageways for the assembled dryer. The lower portion 61 of each of the units 40 has side walls 77 within which clean-out inspection openings 78 are formed. The openings 78 are covered by insulated side covers 79 similar to the side covers 68 on the upper portion 60.

The lower portion 61 of each of the units 40 includes an arcuately formed, sheet metal nozzle assembly 80 arranged to overlie a segment of the dryer shell to direct hot gases into impingement with the exposed surface of the paper web, and to withdraw moist gases from such surface. The nozzle assembly 80 is formed in the lower portion 61 of the unit 40 between enclosing end plates 83 and 84 and the side walls 77 which, with the partition 65, enclose the lower portion 61 as a box-like structure.

The nozzle assembly 80 is shown in FIGS. 8 and 9 as being formed with a curved plenum chamber 85 received between the end plates 83 and 84 and communicating with a plurality of air discharging nozzles 90. The nozzles 90 are essentially wedge-shaped as viewed from the end, and fan-shaped from the side, as shown in FIG. 9b, and are open at their top into the plenum chamber 85. The outlets 91 of the nozzles 90 form longitudinal slits substantially the depth of the unit which align with the slits of similar nozzles 90 in adjacent units. The

5
upper portion of the nozzle assembly 80 forms a neck 92 which opens into the hot air supply duct 74 through an inlet opening 95 formed in the partition 65. Several curved deflectors 96 may be placed in the neck 92 to aid in the distribution of air from the opening 95 to the nozzles 90.

10
The nozzles 90 are arranged to direct the hot air from the inlet duct 74 into impingement with the surface of a web on the dryer shell 33. Pairs of end nozzles 97 are arranged to direct air inwardly and somewhat tangentially to the web to reduce the loss of air along the entrance and exit edges of the dryer.

15
The nozzle assembly 80 further includes a plurality of openings 100 disposed in rows between the nozzles 90 for the removal of moist air from the zone adjacent the surface of the web. These openings 100 communicate with the interior of the lower portion forming a return air chamber 101 which interior is in turn opened into the return duct 75 at a return opening 102 formed in the partition 65. Larger openings 103 are formed adjacent the inclined nozzles 97 for the purpose of collecting moist air at these regions with the reduction of air loss along the edges of the dryer.

20
25
30
35
40
45
50
55
The nozzle assemblies of each of the units for controlling the rate of hot air flow to the nozzles and the rate of return from the openings 100 and 103. More specifically, a first damper plate 105 is slidably mounted on the partition 65 and selectively movable to cover the inlet opening 95, and a second damper plate 106 is similarly situated with respect to the outlet opening 102. As shown in FIGS. 6 and 7, the plates 105 and 106 are arranged for sliding movement within damper guides 108 fixed to the partition 65, and are interconnected for concurrent adjustment by a damper or tie rod 110. The rod 110 is secured to the damper plates by means of nuts 111 welded to the upper surfaces of the plates, and is arranged to move transversely of the dryer through a tubular guide bushing 112 in the wall 62 and a similar bushing 113 in the divider 70.

45
50
55
The damper plates may be remotely controlled by means of a damper unit assembly including a diaphragm-operated air motor 115 suspended on a hangar bracket 116 secured to the top of each of the units 40. The motor 115 is arranged to have air pressure extending action and spring return to position the damper rod 110 and the attached damper plates through a bell crank 117 and a clevice pin 118 attaching the bell crank to the rod 110.

55
60
65
70
75
It is understood that the inlet and outlet dampers may be manually adjusted where automatic moisture control or remote positioning is not desired. Either manual or remote control may be employed to provide for the profile control of the moisture content of the moving web by controlling the rate of hot air application and moist air withdrawal at transverse arcuate segments of the dryer shell.

60
65
70
75
The operation of the dryer is further controlled through a position limit switch arrangement for defining the maximum open position of the assembled units 40 on the side rails 17 and 18 for threading and the closed or lowered position of the units for drying. Referring to FIG. 10, a bracket 120 is mounted on one of the transverse support bars 15 and extends upwardly therefrom adjacent the channel rail 18. A pair of limit switches 121 and 122 are adjustably mounted on the bracket for engagement with a cam 124 carried on the adjacent rail 18 to define the limits of radial movement of the dryer shell. As an example, it has been found that a 9-inch rise provides clearance sufficient for threading purposes. The uniform operation provided by the jacks 20, including their direct mechanical interconnection, permits a minimum running clearance in the order of $\frac{1}{4}$ to $\frac{3}{8}$ of an inch, this being dictated by the roundness of the dryer shells. Such minimum clearance is readily obtained once the limit switches 121 and 122 have been properly adjusted after each subsequent threading of the dryer.

The number of the units 40 making up the dryer body for a given installation is dependent upon the width of web to be dried. The width of the individual units is preferably such that permits effective control of the moisture content transversely of the web through the adjustable dampers, and a unit width of 12 inches has been found satisfactory, as an example.

The units 40 are placed in contiguous relation on the rails 17 and 18 to form the dryer body and are separated by high temperature gaskets at the end plates 83 and at the flanges 69. A plurality of tie bolts 130 are extended through tie bolt openings formed by short sections of tubing 131 through the units 40 and extend to receive retaining nuts 132 and springs 133, as shown in FIG. 1. The tie rods 130 and springs 133 provide for the expansion of growth of the dryer body with the rails while providing for a constant seal between the units with contraction and expansion.

In the operation of the dryer, the motor 30 is operated to rotate the screw jacks 20 through the miter drives 24-25 and shafts to apply a uniform rate of rise at the four corners of the dryer defined by the plates 21, thereby moving the assembled units 40 radially outward from the dryer shell. The upper limit switch 121 may be adjusted to define the extent of this movement, as desired.

After threading in the usual manner, the reversible motor 30 may be again energized to lower the dryer into its operative position. Any unevenness of the dryer with respect to the dryer shell may be initially compensated for by the loosening of the couplings 34 and the individual rotation of the screw jacks 20, as necessary. The lower limit position will therefore be maintained with accuracy throughout the subsequent use of the lifting mechanism, and the lower limit switch 122 may be adjusted to cause the dryer to return to the desired working position.

Hot air from a suitable furnace is applied under pressure through the external inlet duct 49 to the inlet supply passageway defined by the inlet duct portions 74 of the several units. This hot and dry air is then applied to the moving surface of web through the adjustable inlet 95 and the nozzles 90 and 97. Moist air is withdrawn from the surface through the openings 100 and 103 through the adjustable outlet opening 102 and the outlet passageway in the dryer defined by the outlet ducts 75.

The insulated cover 67 and side panels 68 and 79 serve to retain much of the heat energy within the dryer, and such side panels are removable to provide access into the dryer units for cleaning. Also, the doors 47 and 48 provide access for cleaning, adjustment, and maintenance purposes. The inlet and outlet dampers may be adjusted, as desired, to provide predetermined drying results such as profiling, and this may be accomplished either through limit or automatic control.

While the form of apparatus herein described constitutes a preferred embodiment of the invention, it is to be understood that the invention is not limited to this precise form of apparatus, and that changes may be made therein without departing from the scope of the invention which is defined in the appended claims.

What is claimed is:

1. A dryer unit adapted for use with a plurality of similar units in contiguous relation to form a complete dryer for removing moisture from a moving web of paper, comprising an upper portion and a lower portion separated by a partition, an arcuately shaped nozzle assembly in said lower portion adapted to be positioned adjacent a segment of a dryer shell for removing moisture from a web on such shell and having a plurality of nozzles arranged to impinge heated air against the exposed surface of such web, said assembly further having means in said lower portion defining a plurality of openings for withdrawing moist air from adjacent the surface of the web, means in said lower portion defining a hot air plenum chamber connected to supply air to said nozzles and a

return air chamber arranged to receive moist air from said openings, means in said upper portion forming a segment of a hot air supply duct and a segment of a moist air return duct, a first variable damper positioned in said partition between said supply duct segment and said plenum chamber to regulate the rate of air flow from said duct through said nozzles and a second variable damper connected for movement with said first damper and positioned in said partition between said return duct segment and said return air chamber to regulate the moist air return rate through said openings.

2. A dryer for removing moisture from a moving web of paper passing over a drying shell, comprising a pair of longitudinally extending support rails adapted to be positioned adjacent the shell on opposite sides thereof, a plurality of separate drying units mounted in contiguous relation on said rails and having a total width at least as wide as the web, means in each said units for directing hot gases into impingement with the web and for removing moist gases therefrom, rod guide tubes transversely positioned in each of said units and arranged to be in alignment with similar tubes in adjacent units in said contiguous relation to form transverse tie rod openings, tie rods received in said openings and arranged to extend through the combined width of said units, and retaining means on the extended ends of said tie bolts for holding said units in compression and providing for the expansion thereof upon heating.

3. A dryer for removing moisture from a moving web of paper passing over a drying shell, comprising a plurality of separate drying units mounted in contiguous relation transversely of the shell and having a total width at least as wide as the web, means in each said units for directing hot gases into impingement with the web and for removing moist gases therefrom, rod guide tubes transversely positioned in each of said units and positioned for alignment with similar tubes in adjacent units in said contiguous relation to form transverse tie rod openings, tie rods received in said openings and arranged to extend through the combined width of said units, nuts on the extended ends of said tie rods, and compression springs interposed between said nuts and the adjacent said unit to hold said units in compression one against the other and to provide for the expansion thereof upon heating on said tie rods.

4. A dryer for removing moisture from a moving web of paper passing over a drying shell, comprising a pair of longitudinally extending spaced apart support rails adapted to be positioned adjacent such shell on opposite sides thereof, a dryer body mounted on said rails and having a width at least as wide as the web, means in said body for directing hot gases into impingement with the web and for removing moist gases therefrom, a pair of support stands positioned adjacent each end of said rails and having a mechanical screw jack positioned in lifting relation to each end of said rails, mechanical means interconnecting said jacks for simultaneous operation to move said dryer body radially inward and outward in relation to the shell, and means for separately adjusting each of said jacks for the initial leveling of said dryer body in relation to the shell.

5. A dryer for removing moisture from a moving web of paper passing over a drying shell adapted for easy threading and accurate return to a predetermined drying position, comprising a pair of longitudinally extending support rails adapted to be positioned adjacent such shell on opposite sides thereof, a dryer body mounted on said rails and having a width at least as wide as the web, means in said body for directing hot gases into impingement with the web and for removing moist gases therefrom, support means positioned adjacent each end of said rails and having a mechanical screw jack positioned in lifting relation to each end of said rails, mechanical means interconnecting said jacks for simultaneous operation to move said dryer body radially inward and outward ad-

ja⁵cent the shell between a drying position and a threading position, each of said jacks being separately adjustable for the initial leveling of said dryer body in relation to the shell, and limit switch means having a connection to said support having adjustable means for limiting the inward movement of said body to a predetermined drying position with controlled and predetermined running clearance.

6. A dryer for removing moisture from a moving web of paper passing over a dryer shell, comprising a plurality of separate drying units each having a width forming a small part of the total width of the web and supported in contiguous relation to each other transversely of the web and with a total width at least as wide as the web, means in each of said units forming a segment of a hot air inlet duct which is open at least on one end of said unit with the opening in alignment with similar said duct segments of adjacent units to form a common hot air passageway, a separate arcuate nozzle assembly forming a part of each of said units arranged to overlie a corresponding segment of the shell and connected to receive air from said inlet duct segment and to direct air in impinging relation against the exposed arcuate surface portion of a web on such shell, each of said units including further means forming a segment of a moist air return duct being open at least on said one end thereof with the opening in alignment with similar duct segments of adjacent units forming a common return air passageway for said dryer, means in said nozzle assembly arranged to receive moist air adjacent said web and opening into said return duct segment, and internal controllable damper means in each of said units positioned between said nozzle assembly and said inlet duct segment for controlling the rate at which hot air is admitted into said nozzle assembly.

7. An individual dryer unit adapted for use in combination with a plurality of similar units arranged in contiguous transverse relation to a dryer shell to form a complete dryer for removing the moisture from a moving web of paper on such shell, comprising a sheet metal body

10 having a width forming a small part of the total width of the web to be dried, said body having an upper portion closed on the top and sides thereof and having at least one open end facing transversely of such web for alignment with similar openings in adjacent said units, said body further having a lower portion separated from said upper portion by a partition, said lower portion including an arcuately shaped nozzle assembly adapted for positioning adjacent a segment of such dryer shell having a plurality of nozzles arranged to impinge heated air against the exposed surface of said web, said assembly further having means defining a plurality of return openings for withdrawing moist air from adjacent the surface of the web, said nozzle assembly further including a hot air plenum chamber formed in said lower portion and opening into said upper portion at one side thereof, divider means in said upper portion forming a hot air duct segment in communication with said plenum chamber and a moist air return segment in communication with said moist air return openings.

15 8. The dryer unit of claim 7 comprising means in said body defining a pair of opposite recesses positioned substantially midway between the top and bottom thereof at said partition for mounting on a pair of parallel support rails.
